UNITED STATES PATENT OFFICE.

CONRAD D. YOUNGBERG AND GEORGE J. RUNDBLAD, OF WOODSTOCK, ILLINOIS, AS
SIGNORS TO WOODSTOCK TYPEWRITER COMPANY, OF WOODSTOCK, ILLINOIS, A
CORPORATION OF ILLINOIS.

LETTER-SPACING MECHANISM FOR TYPEWRITERS.

Application filed December 19, 1924. Serial No. 756,281.

This invention relates to mechanism for effecting letter space movement of a typewriter, and has for its object the provision of such mechanism which shall be of improved construction and operation and in which the operating mechanism is simple and direct, effecting ease of operation and economy of construction.

The invention is exemplified in the combination and arrangement of parts shown in the accompanying drawings and described in the following specification, and it is more particularly pointed out in the appended claims.

15 In the drawings—

Fig. 1 is a vertical section of a typewriter showing one embodiment of the present invention; and

20 Fig. 2 is a fragmentary top plan view of the mechanism shown in Fig. 1.

The invention is shown as applied to a power actuated "Woodstock" typewriter, such as that illustrated in the application of Otto A. Hokanson, Serial No. 732,615, filed 25 August 18, 1924, which has matured into Patent No. 1,614,475, dated Jan. 18, 1927, but it will be understood that the invention is applicable to typewriters other than that shown in the application referred to.

30 The numeral 10 designates the supporting frame for a typewriter in which a power roller 11 is journaled and actuated by a motor 12 mounted at one side of the frame 10. Type bars 13 are pivoted at 14 on any 35 suitable type bar segment and are operated by sub-levers 15 pivoted at 16 on a cross-bar 17. Actuators 18 are pivotally connected at 19 to the sub-levers 15 and are provided with teeth 20 in position to engage the teeth 40 on the power cylinder 11. Key levers 21 are

provided with contact members 22 which engage lugs 23 on the actuators 18 to move them into operative connection with the drum 11. Stops 24 are mounted on swing-ing arms 25 to release the teeth 20 from the teeth on the power drive 11. The key levers 21 are provided with downwardly projecting wedging members 26 which co-operate with rollers 27 to provide interlocking mechanism which prevents depression of more than a single key lever at one time. A line lock lever 28 carries a shoe or wedging

member 26 similar to those connected with the key levers and arranged to be moved between the rollers 27 so that when the line lock lever 28 is rotated in a counter-clock-wise direction, as viewed in Fig. 1, the rollers 27 will prevent depression of any of the key levers 21. The lever 28 is actuated by a bar 29 having an L-shaped slot 30 in its forward end and having its rear end pivoted at 31 to a bell crank lever 32 which is connected by a link 33 to a line lock lever 34. A line lock release key 35 is provided for releasing the lever 28. The parts thus far described are more fully explained and claimed in application, Serial No. 732,615, referred to above, and in Otto A. Hokanson application, Serial No. 709,328, filed April 28, 1924. This mechanism forms a part of 70 the present invention only as it enters into combination with other features.

The typewriter is provided with a cross-bar 36 which is slotted to receive the key levers and which carries the interlocking 75 rollers 27. In front of the cross-bar 36 a rock shaft 37 is pivotally mounted and is provided with forwardly projecting arms 38 which support a space bar 39. Near the center of the machine the rock shaft 37 is 80 provided with an upwardly extending arm 40 which is provided with a link 41 pivoted at 42 thereon. The link 41 is pivoted at 43 at its rear end to a dog rocker 44 which controls the escapement wheel 45. When the 85 space bar 39 is depressed the link 41 will draw the lower end of the dog rocker 44 forwardly, thus permitting a one-step movement of the escapement wheel. This produces a letter space movement of the typewriter carriage in the usual well-known manner.

It will be seen that the letter space operation does not require movement of any heavy parts, nor does it require that the parts 95 strike a blow as in the case of the type keys. Mechanism is provided for actuating the type keys and other parts of the operating mechanism by the power driven cylinder 11, but since the letter spacing requires but 100 slight force this may be done directly by hand with approximately the same exertion as is required to control the power mechanism for operating the other parts of the

typewriter. By placing the rock shaft 37 near the front of the machine, thus decreasing the length of the levers 38, the movement of the space bar 39 may be slight to 5 accomplish the letter space action so that the movement of the letter space bar will correspond closely to the amount of movement of the type keys for controlling the power mechanism. It will be noted that 10 the line lock mechanism while controlling the key levers does not lock the space bar so that it is possible to shift the platen for the letter space movement after the type keys are locked against operation.

15 We claim:—

1. In a typewriter, a plurality of key levers, a slotted guide bar or comb adjacent the front of said typewriter for guiding said key levers, line lock mechanism supported 20 by said guide bar, a rock shaft journaled in said typewriter in front of said guide bar, a space bar secured to said rock shaft, and means actuated by said rock shaft for effecting letter space movement.

25 2. In a typewriter, a power actuated drive, type bars, a single set of key levers, means separate from said key levers but controlled thereby for connecting said power actuated drive with said type bars, a rock shaft journaled in said typewriter in front of said power actuated drive, a letter space bar for actuating said rock shaft, and means actuated by said rock shaft independently of 30 said power actuated drive for effecting letter space movement.

35 3. Typewriter mechanism comprising a frame, a continuously rotating power drive extending across the frame approximately midway between the front and rear thereof and adjacent the bottom of said frame, type 40 bars, means co-operating with said power drive for actuating said type bars, key levers for controlling said actuating means posi-

tioned above the power drive, guiding means for said key levers disposed in front 45 of said power drive and extending transversely of said frame, a rock shaft extending transversely of said frame in front of said guide, a rocker arm on said rock shaft positioned approximately midway of the ends 50 thereof, a link pivotally connected to said rocker arm and extending rearwardly of the frame across said guide and power drive, means for connecting the rear end of said link to the escapement mechanism, and 55 means on the front of the frame in advance of the key levers for actuating said link through said rock shaft.

4. Typewriter mechanism comprising a frame, a toothed roller extending transversely of the frame approximately midway between the front and rear thereof and adjacent the bottom of said frame, a motor for driving said roller, type bars, means cooperating with said roller for actuating said 60 type bars, key levers for controlling said actuating means extending above said roller, a guide for said key levers disposed in front of said roller and extending transversely of said machine, a rock shaft extending transversely of said frame in front of said guide, an upwardly projecting arm on said rock shaft, a substantially horizontal link extending rearwardly from said upwardly projecting arm and supported by said arm above 65 said guide and roller, the rear end of said link being connected with said escapement mechanism, a space bar disposed at the front of said frame, and means connecting said space bar with said rock shaft.

In testimony whereof we have signed our names to this specification on this 16th day of December, A. D. 1924.

CONRAD D. YOUNGBERG.
GEORGE J. RUNDBLAD.
